Primary Examiner — Antoine D Davis*(74) Attorney, Agent, or Firm* — Haynes and Boone, LLP**CLAIM**

The ornamental design for a sensor housing, as shown and described.

DESCRIPTION

FIG. 1 is a front left top perspective view of a sensor housing showing my new design;

FIG. 2 is a front right top perspective view thereof;

FIG. 3 is a front elevational view thereof;

FIG. 4 is a rear elevational view thereof;

FIG. 5 is a a right side elevational view thereof;

FIG. 6 is a left side elevational view thereof;

FIG. 7 is a top plan view thereof;

FIG. 8 is a bottom plan view thereof;

FIG. 9 is a bottom front right perspective view thereof; and,

FIG. 10 is a bottom front left perspective view thereof.

The broken lines shown in the drawings are for the purpose of illustrating environmental matter and/or illustrating portions of the sensor housing that form no part of the claimed design.
